BANANA RACK

John Rakatzky, Bridgeport, Conn.

Application May 15, 1935, Serial No. 21,589

5 Claims. (Cl. 211—96)

This invention relates to new and useful improvements in display means and relates particularly to a banana display rack, and especially one which may be hung in a location and space 5 which previously was not in use and therefore is a space saver and does not interfere with the usual use of other displays.

An object of the invention is to provide a banana display rack which is rotatable or swingable through an arc whereby the entire capacity 10 of the rack may be fully displayed from both sides.

Another object is to provide a rack including hooks so arranged that the hands of bananas will 15 be hung on the hooks with the inner sides of the hands, comprising the larger bananas, disposed outwardly.

A further object is to provide a display rack having the characteristics indicated and which 20 includes a tray for receiving and displaying loose, ripe, bruised or small bunches of bananas.

Other objects and advantages will become apparent from a consideration of the following detailed description taken in connection with the 25 accompanying drawing wherein satisfactory embodiments of the invention are shown. However, it will be understood that the invention is not limited to the details disclosed but includes all such variations and modifications as fall within 30 the spirit of the invention and the scope of the appended claims.

In the drawing:

Fig. 1 is a side elevational view showing a rack 35 constructed according to the present invention;

Fig. 2 is an end elevational view of the rack;

Fig. 3 is a sectional view taken substantially along the plane of the line 3—3 of Fig. 1;

Fig. 4 is an end elevational view showing a modified construction; and

Fig. 5 is a detail view at right angles to Fig. 4.

Referring in detail to the drawing, and at first particularly to Figs. 1, 2 and 3, the rack is shown as comprising a rectangular frame generally designated 10 and including upper and lower bars 45 11 and 12 and end bars 13 and 14. Although the frame shown has two bars, upper and lower, it will of course be understood the invention is not limited to this number but may include more bars if desired. Frame 10 may be of sheet metal 50 or cast as desired, and preferably integral with the end bar 13 of the frame are hinge means such for example as pins 15 through which the frame may be hingedly mounted on any suitable support as for example the post 16. One means of 55 securing the frame to a support comprises thread-

ing the shanks of eye-bolts 17 into the support in properly spaced relation and then hooking or passing the hinge means 15 through such eye-bolts.

Passing through the upper and lower frame bars 11 and 12 are arms 18 projecting for equal distances laterally of the bars and having their outer end portions bent or curved downwardly and inwardly providing inwardly directed hooks 19. The arms 18 pass through the bars below 10 the upper edges of the latter and may be made rigid therewith by soldering or the deposit of weld metal at 20. Hooks 19 have their inner ends sharpened or pointed and each is adapted for use in the suspending of a hand of bananas 21 15 as suggested by the dotted lines in the drawing. The hooks are preferably directed inwardly so the hands of bananas 21 will be suspended on the hooks in such position that the inner bananas of the hands are disposed outwardly and the largest 20 and best bananas are therefore most prominently displayed.

Wooden cross pieces or supporting strips 22 are disposed on the top sides of the arms 18 carried by the frame bar 11 and such strips are 25 notched or recessed in their under sides intermediate their ends as at 23 to accommodate the upper portion of the bar 11 in order that the strips may rest flat against the top sides of the arms 18. Owing to the reception of the upper 30 portion of the bar in the recesses 23 the supporting strips are held against casual movement laterally with respect to frame 10. Disposed on the upper sides of the strips 22 and secured thereto as by screws 24 or other fastening means is a 35 metal tray 25 adapted to receive and display loose, ripe, bruised or small bunches of bananas, as suggested in dotted lines at 26. Bananas in the state mentioned are not suitable for suspending from the hooks 19 but may be carefully supported and displayed on the tray 25. This will 40 reduce waste of ripe or bruised bananas.

With the display rack constructed as disclosed a large number of hands of bananas may be so displayed as to permit of their ready inspection, 45 and loose or bruised or ripe bananas may also be supported in a manner to protect them while yet displaying them. The rack is rotatable or swingable so that the bananas at each side of it may be inspected before purchase, and since the rack 50 is swingable it may be supported on a door post or the like and yet swung to an out of the way position when desired. The parts may be easily kept clean and in an attractive condition and the tray 25 may easily be removed for washing by 55

simply lifting the tray, together with the supporting strips 22, off the frame 10.

Figs. 4 and 5 suggest a slight modification wherein the flat frame 10 of Figs. 1 to 3 is replaced by a frame generally designated 27 and made up of lengths of pipe 28 connected by elbow fittings 29. To accommodate the pipe section comprising the upper part of the frame 27 the wooden supporting strips 22 are provided in their under sides with arcuate notches 30 as will be plain from an inspection of Fig. 4. Aside from this and the substitution of the frame 27, made of pipe sections, for the flat frame 10, the rack of Figs. 4 and 5 is the same as that of the other figures of the drawing and is used in the same manner.

Having thus set forth the nature of my invention, what I claim is:

1. In a display rack, a bar, means for hinging said bar to have it project horizontally from a support, arms projecting from each side of said bar, a hook at the outer end of each of said arms, supporting strips on the upper sides of said arms, and a tray on said strips.

2. In a display rack, a bar, means for hinging said bar to have it project horizontally from a support, arms projecting from each side of said bar below the upper edge thereof, a hook at the outer end of each of said arms, supporting strips notched in their undersides to receive the upper

edge of said bar and extending transversely of the bar and resting on said arms, and a tray on said strips.

3. In a display rack, a frame including upper and lower and a connecting end bar, upper and lower hinge means on said end bar, and arms extending laterally from each side of the upper and lower bars and having their outer end portions bent downwardly and inwardly providing inwardly directed hooks and a tray mounted on the upper bar and extending laterally at the opposite sides thereof.

4. In a display rack, a frame including upper and lower and a connecting end bar, upper and lower hinge means on said end bar, arms extending laterally from each side of the upper and lower bars and having their outer end portions bent downwardly and inwardly providing inwardly directed hooks, supporting strips on the upper sides of the arms of the upper bar, and a tray on said strips.

5. In a display rack, a bar, means for hinging said bar to have it project horizontally from a support, arms extending laterally from each side of said bar, hooks on the outer ends of said arms, supporting strips on the upper sides of certain of said arms, and a tray supported by said strips.

JOHN RAKATZKY.
